UNITED STATES PATENT OFFICE.

JAY LAVENSON, OF PHILADELPHIA, PENNSYLVANIA.

DESIGN FOR A TOOTH-BRUSH.

46,650.

Specification for Design.

Patented Nov. 17, 1914.

Application filed September 26, 1914. Serial No. 863,766. Term of patent 3½ years.

To all whom it may concern:

Be it known that I, JAY LAVENSON, a citizen of the United States, residing in the city and county of Philadelphia, State of Pennsylvania, have invented a new, original, and ornamental Design for Tooth-Brushes, of which the following is a specification, reference being had to the accompanying drawing, forming part thereof.

Figure 1 is a side elevation of a tooth brush showing my new design. Fig. 2 is a plan view thereof. Fig. 3 is an end view thereof.

1 designates the head of the brush, the same being of right lined form, and 2 the handle thereof.

Copies of this patent may be obtained for five cents each, by addressing the "Commissioner of Patents, Washington, D. C."

3 and 4 designate rows of bristles on opposite sides of said head parallel with each other, and with said head in the longitudinal direction of the brush. The edge of the row 3 is convex as at 5, and that of the row 4 is concave, as at 6.

I claim:

The ornamental design for a tooth brush substantially as shown and described.

JAY LAVENSON.
